TRACTOR-TRAILER FIFTH WHEEL
COUPLING MECHANISMWilliam J. Geddert, Alliance, Ohio, assignor to
American Steel Foundries, Chicago, Ill., a corporation of New Jersey

Application October 31, 1951, Serial No. 254,021

3 Claims. (Cl. 280—33.05)

1

This invention relates to fifth wheels and more particularly to a novel fifth wheel coupling mechanism of the type disclosed in U. S. Patent 2,015,313, issued to Edmund P. Kinne.

In coupling mechanisms of this type, pivotally interconnected front and rear jaws are supported for translatory movement, with guide lugs or extensions of said jaws received in complementary guide slots which pivot the rear jaw upwardly to closed position as the jaws move forwardly and which accommodate pivotal movement of the rear jaw downwardly to open position as the jaws move rearwardly with respect to the fifth wheel. A lock is customarily pivoted to the fifth wheel on a substantially horizontal axis for pivotal movement downwardly to lock position with respect to the rear jaw when the latter is closed. The front jaw is adapted for engagement by the king pin of a coupled vehicle, such as, for example, a semi-trailer, whereby said king pin wedges the front jaw forwardly against resilient means to compress the latter before the lock drops to locked position behind the rear jaw. Thus said resilient means is effective to maintain a slack-free condition between the parts of the coupling mechanism when the latter is coupled with the king pin.

In prior art arrangements of this type, excessive coupling pressure by the king pin against the front jaw is occasionally necessary to urge the jaw rearwardly against the resilient means to a point whereat the lock can drop to its locked condition. This phenomenon has been attributed to various causes such as binding of the lock extensions in the guide ways; however, no successful means have heretofore been provided for satisfactorily correcting this condition.

According to the present invention, it has been discovered that engagement of the king pin with the front jaw tends to tilt the latter on a substantially horizontal axis thereby tilting the pivot pin upwardly and tilting the rear jaw downwardly and rearwardly to increase its overlap with the lock. The guide lugs of the jaws normally limit such tilting; however, due to necessary commercial tolerances and wear of the parts in service, these lugs are frequently loose within their guide slots and accommodate sufficient tilting of the jaws so that excessive compression of the resilient means acting against the front jaw is required to move the rear jaw forwardly to a point whereat the lock may drop to locked position.

Such prior art arrangements, for this reason, have either required excessively high coupling

2

forces or when adjustment has been made to reduce compression of the resilient means, the latter has been ineffective to maintain a slack-free condition of the coupling parts with the jaws locked in closed position.

Another disadvantage of the above described prior art arrangements has been excessive wear between the contacting areas of the front jaw and king pin during coupling.

Accordingly, a primary object of the present invention is to eliminate tilting of the front jaw during contact of the king pin therewith during coupling, without the necessity of reducing clearance between the jaw extensions and their guiding slots, an expediency which would result in prohibitive costs.

Another object of the invention is to devise an arrangement wherein tilting of the front jaw is positively prevented despite any wear which may take place in service between the lock extensions and the margins of their guide slots.

A further object of the invention is to reduce wear between the contacting areas of the front jaw and king pin during coupling.

A more specific object of the invention is to devise upper and lower abutments on the front jaw for substantially simultaneous engagement with complementary portions of the king pin during coupling.

The foregoing and other objects and advantages of the invention will become apparent from a consideration of the following specification and the accompanying drawings, wherein:

Figure 1 is a perspective view of a preferred embodiment of the novel coupling mechanism applied to a conventional fifth wheel, which is illustrated in phantom lines.

Figure 2 is a side elevational view of the novel coupling mechanism in coupled relationship with the king pin, the king pin and fifth wheel structure being diagrammatically illustrated in phantom lines for the sake of clarity;

Figure 3 is a view similar to Figure 2 but illustrating the coupling mechanism in fully open position preparatory to a coupling operation, and

Figure 4 is an enlarged, fragmentary central vertical sectional view through the coupling mechanism during a coupling operation.

Describing the invention in detail, the preferred embodiment illustrated in the perspective view of Figure 1 is applied to a conventional fifth wheel 2, pivoted at each side thereof on a substantially horizontal axis as at 4, to a bracket 6 adapted for attachment to the frame 7 of a vehicle (not shown) such as an automotive truck.

The novel coupling mechanism comprises front and rear jaws 8 and 10, respectively, pivotally interconnected to each other as at 12, by a pivot pin or other suitable means affording pivotal connection between the jaws on a substantially horizontal axis. The pin 12 also connects the jaws to each other for translatory movement as a unit to the closed position shown in Figure 2 and to the open position shown in Figure 3; and it will be noted that these jaws are provided at each side thereof with conventional extensions or lugs 14 and 16, respectively, slidably movable along a conventional support and guide ledge 18 defining the lower margin of a guide slot 20 receiving said lugs 14 and 16. The ledge 18 terminates at its rear extremity in a downturned segment or portion 22 accommodating pivotal movement of the rear jaw 10 downwardly to its open position shown in Figure 3 as the jaws move rearwardly during withdrawal of a king pin 24 of a coupled vehicle, such as a semi-trailer.

The rear jaw 10 is locked in the closed position of Figure 2 by a lock generally designated 26 which is pivoted as at 28 on a substantially horizontal axis to the fifth wheel 2, said lock having one or more legs 30 projecting forwardly from said axis 28 for abutment as at 32 with rearwardly facing surfaces of the rear jaw 10 to lock the jaws in the closed position of Figure 2 whereat the king pin 24 is in coupled relationship confined between the jaws.

As best seen in Figure 4, the king pin 24 is provided at its lower end with a retainer flange 31 which in coupled position of the king pin underlies a retainer ledge or lug 33 formed as a segment of a ring on the rearwardly facing arcuate surface of the front jaw 8. Thus accidental uncoupling of the king pin 24 by upward movement thereof is positively prevented by abutment of the flange 31 with the ledge 33 of the front jaw 8.

The lock 26 is preferably resiliently biased to locked position thereof shown in Figure 2 by spring means herein illustrated in the form of a compression spring 35 compressed between the leg 30 and an overlying surface of the fifth wheel 2, although it will be understood that other forms and combinations of springs may be utilized for this purpose, as disclosed in a co-pending Kayler application, Serial No. 105,080, filed July 16, 1949.

The lock 26 is pivoted upwardly to unlocked position by any desired conventional operating means, such as those described in said co-pending application whereupon the king pin 24 may be withdrawn from the coupled position thereof by forward movement of the fifth wheel 2 or by rearward movement of the king pin 24, whereupon the jaws assume the fully open position of Figure 3.

The forward surface of the front jaw 8 bears in the usual manner against spring means in the form of a block 38 of resilient material such as rubber which is compressible between the lock 8 and a front wall 39 of the fifth wheel as the king pin moves the jaw 8 forwardly during a coupling operation until the lock leg 30 drops from the lock supporting surface 36 of the rear jaw 10 to engage its surface 32, whereupon coupling is completed and the block 38 is effective to maintain the parts in a slack-free condition.

In prior art arrangements of this type, relative forward movement of the king pin 24 to the left, as seen in Figure 3, during a coupling operation caused engagement of the king pin with the front jaw 8 adjacent the upper extremity thereof tending to tilt the front jaw 8 upwardly

about a horizontal axis forwardly of the pivotal connection at 12 to the rear jaw 10. Thus, if the jaw extensions 14 and 16 were sufficiently loose within the guide slots 20, the above described pivotal movement of the front jaw 8 moved the axis 12 upwardly causing downward and rearward movement of the lock supporting surface 36 of the rear jaw 10. Under these conditions, greater than normal forward movement of the front jaw 8 was required to permit downward movement of the lock leg 30 from the surface 36 to the surface 32 against which the leg 30 bears in locked position of the lock 26. For this reason, greater than normal compression of the resilient block 38 was required during coupling.

In accordance with the present invention, the front jaw 8 is formed with abutment surfaces 40 and 42 above and below its ledge 33 as well as the horizontal plane of its center of gravity. The surfaces 40 and 42 are adapted for substantially simultaneous engagement with the king pin 24 and with its retainer flange 31, respectively, as best seen in Figure 4. By means of this novel arrangement, tilting or pivoting of the front jaw 8 is positively prevented during forward movement thereof as the king pin 24 moves the front jaw 8 forwardly to compress the block 38 accommodating movement of both jaws to a point whereat the lock leg 30 may drop to the locked position shown in Figure 2.

It will be further understood that by means of the novel arrangement, commercial tolerances may be observed in the manufacture of the lock extensions 14 and 16, as well as the slot 20, inasmuch as reasonable looseness of the extensions within the slot may be afforded without causing coupling difficulties. Furthermore, the improved device is capable of much longer life in service inasmuch as wear of the lugs 14 and 16 and the margins of their slot 20 will not interfere with ease of coupling.

I claim:

1. In a fifth wheel coupling mechanism; the combination of front and rear jaws pivotally interconnected for translatory movement forwardly and rearwardly with respect to the fifth wheel, a guide ledge on the fifth wheel engaged with an extension on the rear jaw for pivoting the rear jaw upwardly to closed position thereof during forward movement of the jaws, compression spring means between the front jaw and a front wall of said fifth wheel for yieldingly resisting forward movement of said jaws to the closed position of said rear jaw, and vertically aligned rearwardly facing king pin abutments on the front jaw above and below the horizontal plane of its center of gravity.

2. In a fifth wheel coupling mechanism; the combination of front and rear jaws pivotally interconnected for translatory movement forwardly and rearwardly with respect to the fifth wheel, lateral extensions on said jaws received within guide slots of said fifth wheel, said slots having downturned rear extremities accommodating pivotal movement of the rear jaw downwardly to open position thereof during rearward movement of the jaws, a lock engageable with an upwardly facing surface of the rear jaw in open position thereof and engageable with a rearwardly facing surface of the rear jaw in closed position thereof, spring means between the front jaw and a front wall of the fifth wheel for resisting forward movement of the jaws to the closed position of the rear jaw, an abutment on the

front jaw between its upper and lower extremities adapted to overly a retainer flange of an associated king pin confined between said jaws in closed position thereof, and vertically aligned king pin abutment surfaces on said front jaw above and below said abutment.

3. In a fifth wheel coupling mechanism for a king pin having a retainer flange; the combination of hinged front and rear jaws having lateral extensions received within guide slots of said fifth wheel, a downwardly facing abutment on the front jaw for engagement with a retainer flange of said king pin to limit upward movement

thereof, and vertically aligned rearwardly facing king pin abutment surfaces on said front jaw disposed above and below said abutment, respectively, for engagement with said king pin and flange during coupling or buffing.

WILLIAM J. GEDDERT.
